ABSTRACT

Adamantoyl, adamantyl or adamantylalkyl-oxyalkyl 2-aminoethyl phosphates and phosphonates having renin inhibitory activity.

9 Claims, No Drawings

ADAMANTYL-SUBSTITUTED-ALKYL 2-AMINOETHYL PHOSPHATES AND PHOSPHONATES

This invention relates to adamantyl-substituted-alkyl 2-aminoethyl phosphates and phosphonates.

The compounds of this invention have renin inhibitory activity. Renin is an enzyme which is released from the kidney into the bloodstream where it acts upon a substrate, an α -2-globulin, in blood plasma to form a decapeptide, angiotensin I. A converting enzyme acts upon this substance to produce angiotensin II which is a very potent pressor substance. A renin inhibitor is therefore useful in reducing blood pressure of renal hypertension.

The activity of the compounds of this invention as renin inhibitors is demonstrated by biochemical assay and rat bioassay procedures.

In the biochemical assay procedure, renin substrate is incubated with renin and the compound to be tested, and the angiotensin I formed is hydrolyzed in vitro with converting enzyme to give angiotensin II and histidyl-leucine. The amount of histidyl-leucine is then measured spectrophotofluorometrically.

In a rat bioassay procedure, as described by Pickens et al., Circulation Research 17:438-448 (1965) and Sen et al., Biochemistry 6:1572-1581 (1967), activity of the compounds of this invention is demonstrated at about 2 to 10 mg./ml. Briefly, according to this procedure, the compound to be tested, renin and renin substrate are allowed to react in vitro and the angiotensin I formed during the in vitro procedure is measured by pressor effects in anesthetized rats elicited by the angiotensin II formed by the animal's converting enzyme.

The compounds of this invention are represented by the following formula:

FORMULA I

in which:

Y is an alkylene chain of one to four carbon atoms having zero to two lower alkyl substituents;

R₁ is 1-adamantoyl or 1-adamantyl-(CH₂)_n;

n is 0 to 2;

Advantageous compounds of this invention are represented by Formula I in which Y is a straight alkylene chain of one to four carbon atoms.

Preferred compounds of this invention are represented by Formula I in which Y is a straight alkylene chain of one to four carbon atoms and R₃ is

The compounds of this invention are prepared by the following procedures:

The terms Y, R₁ and R₂ are as previously defined; R₇ is hydroxy, hydroxy protected by, for example, 2,2,2-trichloroethoxycarbonyl or benzyl, or iodo and R₇' is hydroxy when R₇ is hydroxy or a protected hydroxy group, or iodo when R₇ is iodo.

The adamantyl substituted intermediates of Formula III are prepared by incorporating 1-adamantoyl or 1-adamantyl-(CH₂)_n on an alkanol starting material of Formula II by methods generally known to the art for preparing O-substituted alkanol compounds, for example as follows.

The compounds of Formula III in which R₁ is 1-adamantoyl are prepared by reacting an excess of an alkanol of Formula II in which R₇ is hydroxy, 2,2,2-trichloroethoxy-carbonyloxy or iodo with 1-adamantoyl chloride and when R₇ is trichloroethoxycarbonyloxy, removing the trichloroethoxy-carbonyl protecting group with acid.

The compounds of Formula III in which R₁ is 1-adamantyl-methyl(or ethyl) are prepared by reacting an alkanol of Formula II, as the sodium salt, in which R₇ is hydroxy or benzyloxy (prepared by reacting an alkanediol with benzyl chloride in the presence of base such as potassium hydroxide in a solvent such as benzene) with a 1-adamantyl-methyl(or ethyl) methylsulfonate, p-toluenesulfonate or halide and when R₇ is benzyloxy, removing the benzyl protecting group by hydrogenation using a catalyst such as palladium in a solvent, for example ethyl acetate or acetic acid.

The compounds of Formula II in which R₁ is 1-adamantyl are prepared by reacting an alkanol of Formula II in which R₇ is benzyloxy with p-toluenesulfonyl chloride, reacting the resulting O-benzyl-O-p-toluenesulfonylalkanediol with the sodium salt of 1-adamantanone (prepared by reacting 1-adamantanone with sodium hydride in dimethylsulfoxide) and then removing the benzyl group by hydrogenation.

The intermediates of Formula III are converted to the phosphate and phosphonate compounds of this invention by the following procedures:

55 According to procedure I, an adamantyl substituted alkanol intermediate is reacted with dichloro N-(2,2,2-trichloroethoxycarbonyl)-2-aminoethyl phosphate in the presence of a base such as pyridine and the resulting intermediate is treated with zinc in acetic acid to give the adamantyl-substituted-alkyl 2-aminoethyl phosphate.

By the method of procedure II, an O-adamantoyl iodoalcohol is reacted with silver t-butyloxycarbonyl-2-

aminoethyl phosphate and the resulting intermediate is treated with acid to give the adamantoyloxyalkyl 2-aminoethyl phosphate.

III.

According to procedure III, an adamantyl substituted alkanediol is reacted with dichloro 2-phthalimidoethylphosphonic acid and the resulting intermediate is treated with hydrazine to give the adamantyl-substituted-alkyl ester of 2-aminoethyl-phosphonic acid.

IV.

According to procedure IV, an adamantyl substituted alkanediol intermediate is treated with p-toluenesulfonyl chloride, the resulting O-adamantyl substituted O-p-toluenesulfonylalkanediol is treated with sodium diethyl phosphonate and the resulting adamantyl substituted alkylphosphonate is treated with acid or base to give the adamantyl-substituted-alkylphosphonic acid which is then converted to the optionally N-substituted aminoethyl or quaternary ammonium ethyl ester.

V.

m is 0 to 1.

According to procedure V, an adamantyl substituted alkanediol intermediate is reacted with dichloro 2-bromoethyl phosphate or phosphonic acid and the resulting intermediate is reacted with an optionally N-substituted amine to give an adamantyl-substituted-alkyl optionally N-substituted aminoethyl or quaternary ammoniumethyl phosphate or an adamantyl-substituted-alkyl ester of optionally N-substituted aminoethyl- or quaternary ammoniumethylphosphonic acid.

In the above procedures I to V, the terms Y, R₁ and R₃ are as previously defined and R₁' is 1-adamantoyl.

As indicated in the following examples the intermediates and the products of this invention may be purified by chromatography using adsorbents such as Florisil (magnesium-silica gel), silica gel or Super-Cel (infusorial earth).

The term "lower alkyl" where used herein denotes groups having one to four, preferably one to two, carbon atoms.

The following examples are not limiting but are illustrative

of compounds of this invention and methods of preparing them.

EXAMPLE 1

5 A solution of 8.85 g. of 1-adamantoyl chloride in 30 ml. of dry chloroform is added dropwise to a solution of 13.66 g. of 1,3-propanediol (azeotroped with benzene and dried over molecular sieves), 4.32 ml. of dry pyridine and 20 ml. of dry chloroform, cooled and stirred at 0° C. The solution is then 10 stirred overnight at room temperature, diluted with ether, washed with dilute hydrochloric acid, water, 5% aqueous sodium bicarbonate solution and water, then dried over sodium sulfate, concentrated and chromatographed on Florisil, eluting with petroleum ether-ether. Concentrating in vacuo and 15 recrystallizing from petroleum ether gives 3-(1-adamantoyloxy)propanol.

A solution of 8.92 g. of dichloro N-(2,2,2-trichloroethoxy-carbonyl)-2-aminoethyl phosphate in 50 ml. of dry chloroform is stirred and cooled under nitrogen and a solution 20 of 2 g. of 3-(1-adamantoyloxy)propanol, 2 ml. of pyridine and 50 ml. of dry chloroform is added dropwise over 1.5 hours. The solution is stirred overnight at room temperature, then diluted with ether, washed with dilute hydrochloric acid and water, dried over sodium sulfate and concentrated to give O- 25 3-(1-adamantoyloxy)propyl O-2-[N-(2,2,2-trichloroethoxy-carbonyl)amino]ethyl phosphate. This intermediate is stirred overnight with 20 g. of activated zinc, 30 ml. of ether and 30 ml. of 90% acetic acid. The reaction mixture is filtered, the filter cake washed with chloroform and the filtrates concentrated. The residue is dissolved in chloroform, washed with small volumes of brine, dried over sodium sulfate and concentrated. The residue is chromatographed on 30 200 g. of 2:1 silica gel - Super-Cel and eluted with chloroform and chloroform-methanol mixtures to give, after concentrating the 3:1 and 1:1 chloroform-methanol eluates and recrystallizing the residue from methanol-acetone, O-3-(1-adamantoyloxy)propyl O-2-aminoethyl phosphate.

EXAMPLE 2

40 11.95 Grams of a 60.2% mineral oil dispersion of sodium hydride is suspended in 300 ml. of dry dimethylsulfoxide and the mixture is heated in an oil bath at 65°-70° C. for two hours under nitrogen. A solution of 22.8 g. of 1,3-propanediol in 50 ml. of dry dimethylsulfoxide is added dropwise to the hot solution and the mixture is heated and stirred for 2 hours. A solution of 12.2 g. of 1-adamantylmethyl methylsulfonate (prepared from 1-adamantylmethanol and methylsulfonyl chloride in pyridine) in 60 ml. of dry dimethylsulfoxide is 45 added and the mixture is heated at 95° C. for 3 days.

The reaction mixture is poured into ice water, extracted with ethyl acetate and washed with water. The extract is dried over sodium sulfate, concentrated and chromatographed on 530 g. of Florisil eluting with petroleum ether and petroleum ether-ether mixtures to give 3-(1-adamantylmethoxy)propanol.

By the procedure of Example 1,3-(1-adamantylmethoxy)-propanol in chloroform and pyridine is reacted with dichloro N-(2,2,2-trichloroethoxy-carbonyl)-2-aminoethyl phosphate. 60 The resulting intermediate is treated with zinc and acetic acid according to the procedure of Example 1 to give O-3-(1-adamantylmethoxy)propyl O-2-aminoethyl phosphate.

EXAMPLE 3

65 A solution of 12.6 g. of 2-(1-adamantyl)ethanol in 70 ml. of anhydrous pyridine is cooled to 0° C. and treated dropwise with 12.0 g. of methylsulfonyl chloride. The mixture is stirred at 0° C. for 2 hours and at 25° C. for 4 hours, then diluted with 70 500 ml. of ether and washed rapidly with cold water, iced dilute hydrochloric acid, water, cold 5% aqueous sodium bicarbonate solution and water. The solution is dried over sodium sulfate and concentrated to give 2-(1-adamantyl)ethyl methylsulfonate.

75 11.39 Grams of a 60.2% mineral oil dispersion of sodium hydride in 200 ml. of dry dimethylsulfoxide is heated at

65°-70 C. for one hour under nitrogen. A solution of 21.74 g. of 1,3-propanediol in 25 ml. of dimethylsulfoxide is added to the cooled solution and the mixture is stirred at room temperature overnight. A solution of 12.3 g. of 2-(1-adamantyl)ethyl methylsulfonate in 25 ml. of dimethylsulfoxide is added dropwise and the mixture is stirred at room temperature for 24 hours. The reaction mixture is diluted with ice water and extracted with ethyl acetate. The ethyl acetate extract is washed with water, dried over sodium sulfate, concentrated and chromatographed on 540 g. of Florisil eluting with 2:1 petroleum ether-ether and 1:1 petroleum ether-ether and ether to give 3-[2-(1-adamantyl)ethoxy]propanol.

According to the procedure of Example 1, 3-[2-(1-adamantyl)ethoxy]propanol is reacted with dichloro N-(2,2,2-trichloroethoxycarbonyl)-2-aminoethyl phosphate in chloroform and pyridine and the resulting intermediate is treated with zinc and acetic acid to give O-3-[2-(1-adamantyl)ethoxy]propyl O-2-aminoethyl phosphate.

EXAMPLE 4

A suspension of 3.67 g. of a 60.2% mineral oil dispersion of sodium hydride in 100 ml. of tetrahydrofuran is dissolved by the portionwise addition of 17.9 ml. of diethyl phosphonate with stirring under reflux. To the solution is added about 5.06 g. of 3-(1-adamantylmethoxy)propyl p-toluene-sulfonate [prepared by reacting 3-(1-adamantylmethoxy)propanol, which is prepared as in Example 2, with p-toluenesulfonyl chloride in pyridine] in 25 ml. of tetrahydrofuran. The mixture is refluxed overnight. The reaction mixture is concentrated under reduced pressure and the residue is dissolved in ether and water and acidified with dilute hydrochloric acid. The aqueous phase is extracted twice with ether. The combined ether extracts are washed with water, dried and concentrated to give the diethyl ester of 3-(1-adamantylmethoxy)propylphosphonic acid.

11.6 Grams of the diethyl ester of 3-(1-adamantylmethoxy)propylphosphonic acid is refluxed for 3 hours with 40 ml. of ethanol and 40 ml. of 20% aqueous sodium hydroxide solution. The reaction mixture is concentrated and the aqueous phase is extracted with ether. The aqueous phase is acidified, extracted with 4:1 ethyl acetate-chloroform and the organic extract is washed with brine, dried over sodium sulfate and concentrated. The residue is dissolved in acetone and treated with cyclohexylamine until basic, then cooled to -30° C. overnight and filtered. The solid material is dissolved in 20 ml. of ethanol and the solution is filtered. The filtrate is concentrated to a small volume and diluted with acetone containing 1% cyclohexylamine. The solution is cooled and filtered. The solid material is recrystallized from ethanol-acetone-1% cyclohexylamine to give 3-(1-adamantylmethoxy)propylphosphonic acid.

3-(1-Adamantylmethoxy)propylphosphonic acid (487 mg.) and 734 mg. of N-(2,2,2-trichloroethoxycarbonyl)ethanolamine are dissolved in 20 ml. of pyridine and 4 ml. of trichloroacetonitrile. The resulting mixture is heated at 50° C. for 30 hours, then concentrated in vacuo. The residue is diluted with water and extracted with ether. The aqueous layer is acidified and extracted with ether. The ether extracts are combined, washed with water and then concentrated in vacuo. The residue is stirred in 20 ml. of 95% acetic acid with 2 g. of activated zinc for 24 hours, then filtered and the filter cake is washed with 4:1 ether-chloroform. The filtrate is washed with water and then chromatographed on 2:1 silica gel - Super-Cel, eluting with 9:1 to 7:3 chloroform-methanol mixtures to give O-2-aminoethyl 3-(1-adamantylmethoxy)propylphosphonate.

EXAMPLE 5

A suspension of 2.37 g. of 2-phthalimidooethyl-phosphonic acid in 25 ml. of thionyl chloride and 3 drops of dimethylformamide is stirred at room temperature overnight. The excess thionyl chloride is evaporated off and the residue is

azeotroped with dry benzene. The resulting dichloro 2-phthalimidooethylphosphonic acid is dissolved in 50 ml. of dry chloroform and a solution of 2 g. of 3-[2-(1-adamantyl)ethoxy]propanol, prepared as in Example 3, 2.65 ml. of dry pyridine and 50 ml. of dry chloroform is added dropwise at 0° C. The mixture is stirred at room temperature for 18 hours, diluted with ether, washed with dilute hydrochloric acid and brine, dried over sodium sulfate and concentrated to give O-3-[2-(1-adamantyl)ethoxy]propyl 2phthalimidooethylphosphonate.

The above prepared phosphonate is dissolved in 50 ml. of 95% ethanol and the resulting solution is treated with 2.43 ml. of 50% aqueous hydrazine and stirred at room temperature overnight. The mixture is concentrated and the residue is stirred with chloroform and filtered and the filtrate is concentrated. The residue is chromatographed on 250 g. of 2:1 silica gel - Super-Cel to give O-3-[2-(1-adamantyl)ethoxy]propyl 2-aminoethylphosphonate.

20

EXAMPLE 6

1.1 Mole of a 60% mineral oil dispersion of sodium hydride in 600 ml. of dry dimethylsulfoxide is heated at 65° C. for 1 hour under nitrogen. The mixture is slightly cooled and 138 g. of 1,6-hexanediol is added. The mixture is stirred at room temperature for one hour. Then a solution of 50.4 g. of 2-(1-adamantyl)ethyl methylsulfonate (prepared as in Example 3) in 100 ml. of dimethylsulfoxide is added and the stirring is continued for 18 hours at room temperature. Ice water is added and the product is extracted into 4:1 (v/v) benzene-chloroform and then washed with water. Chromatography on 2 kg. of Florisil with increasing concentrations of ether in petroleum ether gives 6-[2-(1-adamantyl)ethoxy]hexanol.

A solution of 3.12 g. of 6-[2-(1-adamantyl)ethoxy]hexanol, 4.48 ml. of anhydrous pyridine and 30 ml. of anhydrous chloroform is added dropwise to a cooled and stirred solution of 5.93 g. of dichloro N-(2,2,2-trichloroethoxycarbonyl)-2-aminoethyl phosphate in 30 ml. of chloroform. The solution is stirred at room temperature for 18 hours, then worked up by the procedure described in Example 1 and chromatographed on 500 g. of 2:1 (w/w) silica gel - Super-Cel to give O-6-[2-(1-adamantyl)ethoxy]hexyl O-2-aminoethyl phosphate which after recrystallization from methanol-acetonitrile melts at 229°-231° C.

45

EXAMPLE 7

By the procedure described in Example 6, using in place of 1,6-hexanediol the following alkanediols:

50	1,4-butanediol	O-4-[2-(1-adamantyl)ethoxy]butyl phosphate	O-2-aminoethyl
	1,5-pentanediol	O-5-[2-(1-adamantyl)ethoxy]pentyl phosphate	O-2-aminoethyl
	2-methyl-1,3-propanediol	O-3-[2-(1-adamantyl)ethoxy]-2-methylpropyl phosphate	O-2-aminoethyl
	2-ethyl-1,3-propanediol	O-3-[2-(1-adamantyl)ethoxy]-2-ethylpropyl phosphate	O-2-aminoethyl
55	2,2-dimethyl-1,3-propanediol	O-3-[2-(1-adamantyl)ethoxy]-2,2-dimethylpropyl phosphate	O-2-aminoethyl
	2,3-dimethyl-1,4-butanediol	O-4-[2-(1-adamantyl)ethoxy]-2,3-dimethylbutyl phosphate	O-2-aminoethyl
the products are:			
60	O-4-[2-(1-adamantyl)ethoxy]butyl phosphate	O-2-aminoethyl	
65	O-5-[2-(1-adamantyl)ethoxy]pentyl phosphate	O-2-aminoethyl	
	O-3-[2-(1-adamantyl)ethoxy]-2-methylpropyl phosphate	O-2-aminoethyl	
	O-3-[2-(1-adamantyl)ethoxy]-2-ethylpropyl phosphate	O-2-aminoethyl	
	O-3-[2-(1-adamantyl)ethoxy]-2,2-dimethylpropyl phosphate	O-2-aminoethyl	
70	O-4-[2-(1-adamantyl)ethoxy]-2,3-dimethylbutyl phosphate	O-2-aminoethyl	

70

EXAMPLE 8

A solution of 8.3 g. of 3-(1-adamantoyloxy)propanol (prepared as in Example 1) in 35 ml. of dry chloroform and 21 ml. of dry triethylamine is added dropwise to a solution of 25.5 g. of dichloro O-2-bromoethyl phosphate in 14 ml. of dry

chloroform at 0°-5° C. with stirring. The mixture is allowed to stand overnight in the refrigerator, then stirred for 2 hours and concentrated at room temperature. To the mixture 150 ml. of 0.1N aqueous potassium chloride solution and 40 ml. of 10:1 ether-methanol are added at 0° C. with stirring for 1 hour. The mixture is diluted with 800 ml. of ether and acidified with concentrated hydrochloric acid to pH 2. The ether solution is washed with water, dried over sodium sulfate and concentrated and the residue is azeotroped with benzene to give O-3-(1-adamantyoxy)propyl O-2-bromoethyl phosphate.

A solution of 20 g. of dry gaseous trimethylamine in 200 ml. of 2-butanone is added to 14.7 g. of O-3-(1-adamantyoxy)propyl O-2-bromoethyl phosphate and the mixture is stirred at 50° C. for 18 hours, then concentrated to one-half of its original volume, refrigerated, filtered and dried in vacuo to give O-3-(1-adamantyoxy)propyl O-2-(trimethylammonium bromide)-ethyl phosphate.

Silver carbonate (19 g.) is added to a solution of 9.6 g. of the above prepared ammonium bromide compound with stirring for 3 hours. The mixture is filtered and percolated through a column packed with a 1:1 mixture of weakly basic anion exchange resin (hydroxyl form) and weakly acidic cation exchange resin, eluting with chloroform-methanol to give, after removing the solvent in vacuo, O-3-(1-adamantyoxy)propyl O-2-(trimethylammonium hydroxide)ethyl phosphate.

EXAMPLE 9

By the procedure of Example 8, O-3-(1-adamantyoxy)propyl O-2-bromoethyl phosphate is reacted with triethylamine to give O-3-(1-adamantyoxy)propyl O-2-(triethylammonium bromide)ethyl phosphate which is then converted by the procedure described in Example 8 to O-3-(1-adamantyoxy)propyl O-2-(triethylammonium hydroxide)ethyl phosphate.

By the same procedure, using tributylamine in place of triethylamine, the product is O-3-(1-adamantyoxy)propyl O-2-(tributylammonium bromide)ethyl phosphate which is then converted to the corresponding hydroxide.

EXAMPLE 10

By the procedure described in Example 8, 3-[2-(1-adamantyl)ethoxy]propanol is reacted with dichloro O-2-bromoethyl phosphate to give O-3-[2-(1-adamantyl)ethoxy]propyl O-2-bromoethyl phosphate.

A mixture of O-3-[2-(1-adamantyl)ethoxy]propyl O-2-bromoethyl phosphate and methylamine in 2-butanone is stirred at 50° C. for 18 hours. Working up by the procedure of Example 8 gives O-3-[2-(1-adamantyl)ethoxy]propyl O-2-(N-methyl-amino)ethyl phosphate.

By the same method, using in place of methylamine the following:

ethylamine
butylamine
dimethylamine
dipropylamine
dibutylamine

the products are, respectively:

O-3-[2-(1-adamantyl)ethoxy]propyl ethylamino)ethyl phosphate
O-3-[2-(1-adamantyl)ethoxy]propyl tylamino)ethyl phosphate
O-3-[2-(1-adamantyl)ethoxy]propyl dimethylamino)-ethyl phosphate
O-3-[2-(1-adamantyl)ethoxy]propyl dipropylamino)-ethyl phosphate
O-3-[2-(1-adamantyl)ethoxy]propyl tylamino)-ethyl phosphate.

EXAMPLE 11

Sodium hydride (11.5 g.) in a 60% suspension in mineral oil is suspended in 600 ml. of dry dimethylsulfoxide. The mixture is heated at 65°-70° C. for 2 hours. 1-Adamantanone (46.3 g.) is

added and the resulting mixture is stirred at room temperature for 30 minutes. To the mixture is added 96.2 g. of 3-benzyloxypropyl p-toluenesulfonate (prepared by reacting 3-benzyloxypropanol with p-toluenesulfonyl chloride) in 100 ml. of dimethylsulfoxide. The resulting mixture is heated with stirring at 65° C. for 2 hours, then poured into water and extracted with ethyl acetate. The extract is washed with water and chromatographed over Florisil eluting with ether-petroleum ether mixtures to give 1-(1-adamantyoxy)-3-benzyloxypropane.

The above prepared compound is hydrogenated in ethyl acetate in the presence of palladium at 25° C. for 24 hours to give after filtering and removing the solvent in vacuo 3-(1-adamantyoxy)propanol.

By the procedure of Example 1, 3-(1-adamantyoxy)propanol is reacted with dichloro N-(2,2,2-trichloroethoxy-carbonyl)-2-aminoethyl phosphate and the resulting intermediate is treated with zinc and acetic acid to give O-3-(1-adamantyoxy)propyl O-2-aminoethyl phosphate.

EXAMPLE 12

By the procedure of Example 8, using dichloro 2-bromoethylphosphonic acid in place of dichloro O-2-bromoethyl phosphate, the product is O-3-(1-adamantyoxy)propyl 2-(trimethylammonium bromide)ethylphosphonate which is then converted to the corresponding hydroxide.

EXAMPLE 13

3-(1-Adamantylmethoxy)propylphosphonic acid, prepared as in Example 4, is reacted with 2-methylaminoethanol in the presence of excess trichloroacetonitrile and pyridine (to make the mixture basic) in acetonitrile with stirring at about 50° C. for 30 hours. Water is added and the mixture is acidified with dilute hydrochloric acid, then extracted with ether. The ether extract is chromatographed on silica gel - Super-Cel to give O-2-(N-methylamino)ethyl 3-(1-adamantylmethoxy)propylphosphonate.

By the same procedure, using choline in place of 2-methylaminoethanol, the product is O-2-(trimethylammonium hydroxide)ethyl 3-(1-adamantylmethoxy)propylphosphonate.

What is claimed is:

1. A compound of the formula:

in which:

Y is an alkylene chain of one to four carbon atoms having zero to two lower alkyl substituents;

55 R₁ is 1-adamantoyl or 1-adamantyl-(CH₂)_n;
n is 0 to 2;

2. A compound according to claim 1 in which Y is a straight alkylene chain of one to four carbon atoms.

3. A compound according to claim 1 in which Y is a straight alkylene chain of one to four carbon atoms and R₃ is

4. A compound according to claim 1 in which Y is

CH_2 , R_1 is 1-adamantoyl and R_2 is

5. A compound according to claim 1 in which Y is

CH_2 , R_1 is 1-adamantylmethyl and R_2 is

6. A compound according to claim 1 in which Y is

CH_2 , R_1 is 2-(1-adamantyl)ethyl and R_2 is

7. A compound according to claim 1 in which Y is

5 CH_2 , R_1 is 1-adamantylmethyl and R_2 is

10 8. A compound according to claim 1 in which Y is

15 CH_2 , R_1 is 2-(1-adamantyl)ethyl and R_2 is

20 9. A compound according to claim 1 in which Y is

$(\text{CH}_2)_4$, R_1 is 2-(1-adamantyl)ethyl and R_2 is

* * * * *
